CAN OPENER

Nicholas S. Eckmayer, Chicago, Ill.

Application February 28, 1948, Serial No. 12,010

2 Claims. (Cl. 30—123)

1

This invention relates to can openers, and has for an object the provision of new and improved can openers, particularly suitable for quickly opening beer cans, and which are suitable for opening other types of cans as well.

Another object of the invention is to provide a can opener having a cutting blade, which is carried within a tubular support, or applicator, and wherein the tubular support is adapted to be telescopically disposed about a can to be opened, and upon relative movement, cause the cutter to pierce the top of the can to be opened, and form a substantially triangularly shaped aperture similar to that made by ordinary beer can openers.

A further object of the invention is to provide an applicator and cutter of the type mentioned, wherein the applicator may be telescopically engaged with a can to be opened, moved to pierce the same, and then relatively rotated with reference to said can, to place a continuous cut therein, and sever the top from the can.

Still another object of the invention is to provide a can opener of the type referred to, wherein a combined opener and drinking cup is provided, that is, after the cutter is employed to pierce the beer can top, the applicator may be removed from the beer can, the contents of the can poured into the applicator, and the latter employed as a drinking cup.

Other and further objects of the invention will appear hereinafter from the annexed specification and claims and from the accompanying drawings, in which:

Figure 1 is a vertical sectional view of the invention, showing the same applied to a can, with the blade or cutter about to enter the can top,

Figure 2 is a view similar to Figure 1, with a portion of the can broken away, and showing the device after the same has been longitudinally moved to effect piercing of the can head by the cutter,

Figure 3 is a plan view from the open end of the applicator, showing the cutter projecting from the bottom wall thereof,

Figure 4 is a perspective, detailed view of a metallic disk from which a portion is struck to form the cutter blade,

Figure 5 is a view similar to Figure 1, showing a slightly modified construction,

Figure 6 shows a view similar to Figure 2, after the can has been pierced by entrance of the cutter blade,

Figure 7 is a horizontal sectional view, corresponding substantially to the line 7—7 of Figure 6,

and showing the cutter at the beginning of a circular cut which is completed by relative rotation of the applicator and can, while

Figure 8 is a perspective view of the exterior of the applicator, showing a roughened or knurled surface to facilitate relative rotation when in use.

As shown in Figures 1 through 4 of the drawing, the tubular applicator, or support 10, comprises a cylindrical tubular wall or sleeve 11, of suitable thickness, closed at one end by a thickened wall or bottom 12, and entirely open at the other end, as indicated at 13 to form a container having one end open and the other end closed.

15 The applicator 10 preferably is molded from suitable plastic material, but may be formed of other material, as metal, for example. Fixed in the thickened bottom wall 12 of the applicator 10, as by molding the same therein, is a metallic disk 14 or plate 14, and struck inwardly from the disk 14 is a cutter blade 15. The cutter blade 15 is inclined somewhat with reference to the long axis of the applicator 10, and projects inwardly from the bottom wall 12 an appreciable distance.

20 The cutter blade 15 is substantially V-shaped in form, and at its outer end terminates in a relatively sharp point 16. The cutter is also transversely curved substantially throughout its length to impart stiffness and rigidity thereto, and the 30 lateral margins of the blade are sharpened, as at 17, to facilitate the operation of the cutting blade.

As illustrated in Figures 1 and 2, the applicator 10 is adapted to be telescopically disposed

35 about an ordinary cylindrical filled beer can indicated at 18 and provided with the usual top wall 19. The applicator or tubular support 10, is of slightly greater diameter than the can, as will be appreciated, it being evident that when the 40 applicator is forced in a longitudinal direction with reference to the can 18, the cutter blade 15 will pierce the top 19 of the can, and by reason

45 of its inclination and shape, the cutter blade will extend the cut radially of the can to form a triangular cut such as that shown at 20 in Figure 2. Usually it is desirable to form more than one of the openings 20 in the can top 19, and to effect this result the applicator 10 is moved to retract the cutter blade, the applicator rotated relatively

50 to the can, and the piercing operation repeated. When one or more holes have been made in the can top, the applicator may be removed, inverted, and beer poured from the can into the applicator, as in a cup or glass, and the beer quaffed from the applicator.

Referring to Figures 5 through 8, the tubular applicator 21, and the knife blade 22, are substantially identical to those already described, with the exception that the wall 23 of the applicator 21 is made considerably shorter, so as to insure that an appreciable portion of the can 24 will project beyond the end of the wall 23 after the cutter blade 22 has penetrated the top 24a of the can 24, as best shown in Figure 6. Although the cutter blade 22 is shown as of the same configuration as that previously described, in some instances it is desirable to cut down or omit the inclination, flatten the blade transversely, or in some cases reverse the transverse curvature thereof. The outer periphery of the applicator 21 near the end 25, may have exterior ribs 26 provided thereon to facilitate grasping by the hand of the user and rotation of the applicator relatively to the can. As shown in Figure 6, the applicator 21 has been manipulated so that the cutter blade 22 has pierced the can top in the manner before described. The applicator is then grasped by one hand of the user, and the projecting end of the can by the other hand, and the can and applicator are relatively rotated. By reason of the sharpened edges 27 of the cutter blade 22, a circular cut is made in the can top and when continued results in the can top being entirely severed from the can. The inception of the circular cutting is illustrated in Figure 7. Contact between the tubular wall of the applicator 21 and the can 24, of course, serves to guide the cutting member in this cutting operation. After the cutting operation is completed, the cup-shaped applicator may be removed, along with the severed can top, and the applicator employed as a measuring or drinking cup, or the like.

While I have illustrated and described the preferred forms of construction for carrying my invention into effect, these are capable of variation and modification without departing from the spirit of the invention. I, therefore, do not wish to be limited to the precise details of construction set forth, but desire to avail myself of such variations and modifications as come within the scope of the appended claims.

What I claim is:

1. A combination can opener and drinking cup comprising a container having one end open and

the other end closed, and a blade in the shape of a V from one end thereof to the other end thereof positioned in said container adjacent one edge of said closed end thereof and secured to said closed end thereof and projecting from said closed end toward the center of said container, said blade being curved in transverse cross section, said container being adapted to be circumposed about a closed can and moved longitudinally of said can until said blade punctures the adjacent closed end of said can and then said container being adapted to be rotated with respect to said can causing said blade to make a circular cut to completely sever said adjacent closed end from said can.

15 2. A combination can opener and drinking cup comprising a cylindrical container having one end open and the other end closed, a plate positioned in said container and secured to said closed end thereof, and a blade in the shape of a V from one end thereof to the other end thereof positioned in said container adjacent one edge of said closed end thereof and secured to said plate and projecting from said plate toward the center of said container, said blade being curved in transverse cross section, said container being adapted to be circumposed about a cylindrical closed can and moved longitudinally of said can until said blade punctures the adjacent closed end of said can and then said container being adapted to be rotated with respect to said can causing said blade to make a circular cut to completely sever said adjacent closed end from said can.

20 3. A combination can opener and drinking cup comprising a cylindrical container having one end open and the other end closed, a plate positioned in said container and secured to said closed end thereof, and a blade in the shape of a V from one end thereof to the other end thereof positioned in said container adjacent one edge of said closed end thereof and secured to said plate and projecting from said plate toward the center of said container, said blade being curved in transverse cross section, said container being adapted to be circumposed about a cylindrical closed can and moved longitudinally of said can until said blade punctures the adjacent closed end of said can and then said container being adapted to be rotated with respect to said can causing said blade to make a circular cut to completely sever said adjacent closed end from said can.

25 4. A combination can opener and drinking cup comprising a cylindrical container having one end open and the other end closed, a plate positioned in said container and secured to said closed end thereof, and a blade in the shape of a V from one end thereof to the other end thereof positioned in said container adjacent one edge of said closed end thereof and secured to said plate and projecting from said plate toward the center of said container, said blade being curved in transverse cross section, said container being adapted to be circumposed about a cylindrical closed can and moved longitudinally of said can until said blade punctures the adjacent closed end of said can and then said container being adapted to be rotated with respect to said can causing said blade to make a circular cut to completely sever said adjacent closed end from said can.
